UNITED STATES PATENT OFFICE.

ALBERT C. FERRIER, OF LINCOLN, NEBRASKA, ASSIGNOR OF ONE-HALF TO WILLIAM J. HILL, OF LINCOLN, NEBRASKA.

SPARK-PLUG.

1,169,628.

Specification of Letters Patent.

Patented Jan. 25, 1916.

Application filed May 24, 1915. Serial No. 30,032.

To all whom it may concern:

Be it known that I, ALBERT C. FERRIER, a citizen of the United States, residing at Lincoln, in the county of Lancaster and State of Nebraska, have invented certain new and useful Improvements in Spark-Plugs, of which the following is a specification.

This invention relates to an improvement 10 in spark plugs, and has for its object to provide such a construction that the carbon produced by burning gas will be automatically removed from the conductor and insulating plug and from the chamber containing these parts, to prevent the formation 15 of a short circuit between the electrical conductor and the ground electrode of the spark plug.

The invention consists of the novel construction, combination and arrangement of parts as described herein and claimed, and as illustrated in the accompanying drawing, wherein,—

Figure 1 is a view of the spark plug in 25 longitudinal section. Fig. 2 is a broken away detail showing parts of the device on an enlarged scale.

Referring to the drawing for a more particular description, numeral 3 indicates the 30 wall of an engine cylinder within which charges of gas may be delivered to be ignited or exploded by means of the spark plug, the electric charge passing from the finger *a* of the conductor 4 through the gap to the metallic finger 5 which is mounted in the hous- 35 ing or ground electrode 6.

In the use of spark plugs as ordinarily constructed, carbon will be deposited on the 40 stem of the insulating plug and will ad- here thereto, and from continued use the deposits often accumulate to such an extent that they form an electrical conductor be- 45 tween the metallic parts of the cylinder and the conductor 4 so that the charges of gas will not be ignited, with the result that fre- 50 quent removals of the spark plug from the cylinder, for purposes of cleaning the parts, are required.

In the present instance the insulating plug 55 7 is provided with an annular stem 8 which is formed convergent, preferably, from its inner end *b* to its terminal, its finger *a* pro- jecting inwardly of the cylinder wall 3 in line with the longitudinal axis of the plug.

55 The metallic part or electrode 6 is provide

with a chamber *c* in communication with the interior of the engine cylinder 3, a cylindrical passageway 9, preferably of uniform diameter, being provided which opens thereon and which communicates with said chamber *c*. Chamber *c* is formed convergent toward the passageway 9 preferably its entire length. The insulating plug is adapted to be disposed with its stem traversing the chamber *c* centrally with its finger *a* dis- 60 posed centrally of the passageway 9, and as thus described an annular space or container 10 will be provided between the walls of members 6 and 8 which will be convergent toward the terminal of the stem 8, the 65 degree of convergence increasing gradually throughout its entire length; and the area in cross-section of said chamber or container 10 constantly decreases in a direction of the 70 terminal of said stem.

In operation, the force of the explosions of ignited gas within the container 10 which successively occur will prevent accumulation 75 of deposits of carbon upon the stem 8, and since the area of the container, transversely considered, is greatest at or near its end re- 80 mote from the cylinder 3, the contents of the container 10 will move into the engine cylinder with force sufficient to maintain the passageway 9 in a condition substantially 85 free from deposits.

Numeral 11 indicates a terminal constrict- 90 ed part of the container 10, communicat- ing with the cylindrical passageway 9. While it is formed convergent toward the 95 passageway 9, the wall of the stem 8 is equi- distantly, transversely considered, from the wall of the metallic housing 6, throughout its length, and it is considered that this construction causes dislodgment of the car- 95 bon from the stem 8 and removal of the car- 100 bon from the passageway 9 more effectively.

Having fully described the several parts and their uses, a further explanation relat- 100 ing to operation is not necessary.

While the preferred construction has been shown and described, I do not wish to be understood as limiting myself to small de- 105 tails, nor to form, size or proportion except so far as pointed out by the claims.

I claim:

1. A spark plug, comprising, in combina- 110 tion with a cylinder, a metallic part having a chamber communicating with the cylinder, an insulating plug having a cylindrical stem

formed convergent from its inner end to its terminal and provided with an electrical conductor, said insulating plug being adapted to be disposed with its stem traversing the chamber of said metallic part to form an annular, convergent chamber circumscribing and extending the entire length of said stem, the degree of convergence of said chamber increasing throughout its entire length in a direction of the terminal of said stem.

2. A spark plug, comprising, in combination with a cylinder, a metallic part having a chamber communicating with the cylinder, an insulating plug provided with an electrical conductor and having a cylindrical stem formed convergent toward its terminal, said insulating plug being disposed with its stem traversing the chamber of said metallic part to form an annular chamber extending substantially to the end and circumscribing the stem with a gradually increasing degree of convergence toward the terminal thereof.

3. A spark plug, comprising, in combination with a metallic part having a longitudinally convergent chamber, an insulating plug having a cylindrical stem formed convergent from its inner end to its terminal and provided with an electrical conductor, said insulating plug being adapted to be disposed with its stem traversing the chamber of said metallic part to form a chamber gradually decreasing in area and extending substantially to the terminal of said stem.

4. A spark plug, comprising, in combination with a cylinder, a metallic part formed with a convergent chamber and a cylindrical

passageway opening on the cylinder and said chamber, an insulating plug having a convergent stem and provided with an electrical conductor having a projecting finger disposed in line with the longitudinal axis of said stem, said insulating plug being disposed with its stem centrally traversing said chamber to provide an annular chamber having an area in cross-section constantly decreasing from the inner end of the stem toward the cylindrical passageway, the electrical conductor being disposed centrally of said cylindrical passageway.

5. A spark plug, comprising, in combination with a cylinder, an electrode formed with a convergent chamber and a cylindrical passageway opening on the cylinder and communicating with the chamber, an insulating plug having a convergent stem and provided with an electrical conductor having a finger extending beyond the stem, said insulating plug being disposed with its stem traversing and terminating substantially at the end of said chamber with its finger disposed centrally of the cylindrical passageway, a longitudinal part of said stem, adjacent to its terminal, being disposed equidistant from the wall of the electrode to provide a constricted passageway opening on said cylindrical passageway.

In testimony whereof, I have affixed my signature in presence of two witnesses.

ALBERT C. FERRIER.
